ABSTRACT

A burn-out furnace having separate upper and lower units with the upper unit being detachably mountable on the lower unit, one of said upper and lower units being the element-containing ceramic furnace and the other of the units being the electronic control therefor with the circuits of the two separate units being connectable by a plug-in male and female jack unit, the male jack being associated with one unit and the female jack being associated with the other unit, additionally in a preferred embodiment the furnace door being pivotably mounted on a support extending from the electronic control unit and the door being openable and closable by a handle detachably connected to the door and mountable in opposite alternative directions for a left-handed operator as opposed to a right-handed operator.

PLUG-IN CHAMBER FURNACE

This invention relates to an improvement in burn-out furnaces.

BACKGROUND OF THE INVENTION

Prior to this invention, for many years there have been manufactured by various manufacturers and sold to diversified industries and research laboratories burn-out furnaces for the burning-out of various chemicals and the like which over a period of continued use eventually result in the etching-out and/or the cracking of the ceramic tiles and the elements associated therewith in the furane-containing compartment of the burn-out furnace which heretofore has been a single unit with the two separate compartments, the one compartment being the furnace itself and the other compartment containing the instrumentation for the electronic controls such as the controlling temperature intensity, duration, and the like. Upon the failure of the ceramic lining and/or the elements of the furnace, for years it has been the practice and the only practical choice to discard the entire unit and repurchase another new unit because of the lack of economy and high cost of and impracticability of taking out the broken ceramics and/or elements and replacing with new elements, together with the cutting of circuit leads and soldering on of new circuit leads, and the like. Additionally involved, is the period required for such a repair during which time the research or industrial facility would be without the use of the needed burn-out furnace. For the above and other reasons, a prior development by the present inventor was a unit having the upper and lower compartments of the unitary unit in which the ceramic insulation was semi-removable and replaceable by another ceramic unit slidable into the furnace compartment; that improvement upon which a patent issued nevertheless requiring extensive workmanship to cut the wire circuits connecting the control compartment with the heating elements and the withdrawal of the deteriorated or broken tiles and the insertion of the new tiles, this as before requiring that the burn-out furnace be out of operation for an extended period of time as well as the cost of the operation together with the cost of the replacement ceramic insulation. All of these matters considered together made such a unit of little practical benefit costwise and timewise as opposed to mere repurchase of a brandnew unit which avoided the cost of repair and the loss of operational time during which repair normally would be taking place, as well as the avoidance of the still high cost of the replacement ceramic insulation.

Another factor involved which made the situation with the burn-out furnaces distasteful to industry was the fact that normally when the furnace ceramics and/or elements went bad — i.e. failed, the electronic controls as well as the door and the containers themselves were otherwise in still reasonably good condition but nevertheless had to be discarded as a total lost investment.

SUMMARY OF THE INVENTION

The present invention is directed to overcoming one or more of the prior problems of the type discussed above, as well as the presence of additional benefits and advantages.

Another object of the present invention is a unit which improves the long term cost-picture economically of the utilization of such units, together with improved adaptability to different workers irrespective of their being left-handed or right-handed respectively.

Other objects become apparent from the preceding and following disclosure.

One or more of the preceding objects are obtained by the present invention as defined hereafter.

10. The present invention broadly is directed to a burn-out furnace combination having at least two separate compartments, one of which compartments houses the heat-insulation such as the furnace ceramics and heating elements, and the other of which compartments 15 houses the electronic controls of a conventional or otherwise desirable type, with one of the compartments being detachably mountable on the other compartment with the connections of their respective circuits being by way of a simple electrical connector unit such as 20 male and female jacks respectively matable with one another, one extending from one compartment's circuit and the other extending from the other compartment's circuit, for example. The unit containing the ceramics or other heat insulation and the heating elements is a 25 disposable unit, easily detachable from the control unit and replaceable by a new furnace-chamber unit newly attachable to the old electronic-component-containing unit. In a preferred embodiment, making the inventive combination even more practical and desirable, the 30 furnace door is mounted on a support extending from the control unit whereby when the entire furnace unit is discarded, the furnace door and its mountings are nevertheless remaining attached to the electronic-control unit, thereby not only salvaging for the continued 35 use the furnace door and support therefor but additionally concurrently avoiding a higher cost of a replacement furnace containing unit. In addition to the above, the conventional arm extendable from the furnace door having a handle thereon for opening and 40 closing the furnace door is detachable by virtue of suitable detaching means such as set screws easily unscrewed, or wing nuts, or the like, whereby the arm may be slid out of its position and inserted from the reverse direction making the arm suitable for manipulation of the door by either a right-handed person or alternatively by a left-handed person. Accordingly, the 45 invention as broadly described above includes several benefits not heretofore obtainable all of which are co-ordinated in obtaining improved utilization of a burn-out furnace by the operating personnel as well as reducing costs of and the elimination of repairs and 50 discard of entire units together with the purchase of new units, it being possible by virtue of the present invention merely to purchase the furnace chamber unit to slidably or otherwise detachably mount the new inexpensive unit as a replacement for the burned-out or otherwise broken furnace unit.

THE FIGURES

60. FIG. 1 illustrates a perspective view of a typical unit of this invention.

FIG. 1a illustrates a perspective enlarged in-part view of the mounting for the door hinge as mounted on the lower unit as well as the particulars of the door hinge mounting.

FIG. 2 illustrates a cross-sectional in-part view taken along lines 2—2 of FIG. 1, illustrating the construction

of a slide connecting device by which the top compartment is slidably connected to the bottom compartment.

FIG. 3 illustrates a perspective in-part view of an alternative embodiment in which the door hinge structure is removably mounted on the upper furnace unit compartment.

FIG. 4 is a rear view of an alternative embodiment shown in FIG. 5, the rear view illustrating upper and lower compartments and mounting means therebetween, with the upper and lower units respectively having mating male and female electrical connectors.

FIG. 5 illustrates a perspective view of an alternative embodiment of this invention basically differing from other embodiments only in that the door is detachably slidably mounted on the furnace chamber.

DETAILED DESCRIPTION OF THE INVENTION

FIG. 1 illustrates a perspective view of a typical burn-out furnace 6 of this invention, illustrating an upper ceramic furnace compartment 7 and a lower instrument compartment 8 detachably connected by a slide connector 9. The furnace door 10 is pivotably mounted by structure 12 around axis 13, held firmly against the axis by set screw 14, with the axis 13 being rotatable in the support 11b mounted on the support 11a which in turn is mounted on the lower compartment 8 as is illustrated in an enlarged view in FIG. 1a. In FIG. 1, on the face of the lower instrument compartment is instrument panel 16, and control knob 20a and dial switch 20b, as typical control levers. Handle 13a is actuatable to open the furnace door 10. By virtue of the detachable handle 13a and axis 13 as a result of removable set screw 14, the axis may be withdrawn from its inserted position and inserted from an opposite direction whereby the furnace door 10 is openable with the handle 13a located on the right side of the unit instead of the left side of the unit, whereby dependent upon the preference of a right-handed or left-handed person, the arm handle 13a is utilizable either as a left-handed or right-handed handle.

FIG. 2 typically illustrates in cross-section the slide mechanism showing the slide female structure 9a mounted on the compartment 7 and the male insert 9 matable therewith and mounted on the lower compartment 8. Compartment 7 includes insulation 115.

FIG. 3 illustrates an alternative embodiment from that of FIG. 1, differing principally only in that the door is removably mounted on the upper furnace compartment by virtue of one or more upwardly extending threaded shafts such as shaft 17 insertable through a respective aperture in the mounting structure 11c, and typically a butterfly female head 18 being screwable downwardly onto the shaft 17. Other parts substantially correspond to those of FIG. 1.

FIG. 4 illustrates the male electrical connector mounted on the upper furnace compartment 7b and having male elements 21a, 21b, and 21c, for insertion into the female unit 23 mounted on connector cord 22.

FIG. 5 illustrates merely a variation on the embodiments illustrated above, whereby the door is slidably mounted and by removal of a set screw in the end of the door is detachable from the tracks 19. Parts substantially correspond to those of other embodiments except for the handle 13c obviously being mounted suitably for the lifting slidably of the door 10b.

As described above under the "Summary of the Invention," the heart of the invention is the economy and

convenience to industry by having a furnace compartment totally detachable from the instrumentation compartment by an easily operated detaching mechanism such as the illustrated slide device. It should be noted that typically a screw such as the phillips screw 14a of FIG. 1a prevents the upper unit from becoming detached from the lower unit. Also, as described above, although it is preferable that the door and hinge mechanism be attached to the lower unit, thereby avoiding the necessity of detaching the door whenever the furnace unit is changed, it is within the scope of the invention to have the door detachably mounted on the furnace unit itself as illustrated for example in FIGS. 3 and 5.

15 Although not illustrated, it is clearly within ordinary skill to adapt the invention to other alternative embodiments such as an embodiment, for example, in which the furnace unit would be on the bottom and the instrumentation compartment would be on the top. Also, although a preferred attaching mechanism of a sliding arrangement identified as slide mechanism 9 and 9a are illustrated, it is clearly within the scope of the invention to use any suitable and/or desirable and/or conventional attaching means by which the two compartments 20 may be easily connected and disconnected with reasonable speed. Also, as an alternative, the male device may be mounted on the instrumentation panel and the female connector mounted on the furnace compartment, or as another typical variation the female element may be mounted within the side of typically the instrumentation unit and the male elements may be mounted on a cord extending from the furnace unit.

25 Similarly, there may be other variations, substitutions of equivalent parts, and modifications as would be apparent to a person of ordinary skill in this field.

30 We claim:

35 1. A plug-in furnace comprising in combination: a furnace unit means defining a heat-insulation-lined heating-chamber having operatively mounted electrical heating elements heatable of the heating chamber, and a first electrical connector jack means for connecting said elements to a power-source and regulator means, said unit means being separate from and including first structure means for removably attaching to a power-source and regulator means, said unit means includes 40 ceramic lining, and a power source and regulator means for regulating furnace temperature having a second electrical connector jack means matable with said first jack means, and second structure means for matably attaching to said first structure, a mounted furnace door means for opening and closing said port through-channel, said door means comprising a hinge-mounted door and an actuating handle, said handle being removably mounted on said door and reversibly mountable and extendable in an opposite direction thereby said handle being mountable for alternatively left-handed and right-handed persons.

45 2. A plug-in furnace comprising in combination: a furnace unit means defining a heat-insulation-lined heating-chamber having operatively mounted electrical heating elements heatable of the heating chamber, and a first electrical connector jack means for connecting said elements to a power-source and regulator means, said unit means including ceramic lining, and a power source and regulator means for regulating furnace temperature having a second electrical connector jack means matable with said first jack means, and second

structure means for matably attaching to said first structure, said furnace unit means and said power-source and regulator means jointly include attaching and locking structure rendering one removably attachable to the other, said unit including ceramic lining, said furnace door means further including port structure defining a port through-channel extending through a wall of said furnace unit and sufficiently large dimensions to insert and remove specimens into and from said furnace respectively, and means for opening and closing 10

said port into said furnace unit means mounted on said power-source and regulator means, and a mounted furnace door means for opening and closing said port through-channel, said door means comprising a hinge-mounted door and an actuating handle, said handle being removably mounted on said door and reversibly mountable and extendable in an opposite direction, thereby said handle being mountable for alternatively left-handed and right-handed persons.
